GUNNER'S CUPOLA FOR AN ARMORED VEHICLE

William A. Webb, Perry Hall, Md., assignor to Aircraft Armaments, Inc., Cockeysville, Md., a corporation of Maryland

Filed Jan. 21, 1960, Ser. No. 59,132

Term of patent 3½ years

(Cl. D14—6)

FIG. 1

FIG. 2

FIG. 3

FIGURE 1 is a front perspective view of a gunner's cupola for an armored vehicle showing the new design with the cupola hatch in closed position and with a portion of the gun barrel broken away for convenience of illustration.

FIGURE 2 is a side perspective view of the cupola showing the hatch in open position.

FIGURE 3 is a top view of the cupola with the hatch in closed position.

Portions of the gun barrel are shown broken away in FIGURES 2 and 3 for convenience of illustration.

I claim:

The ornamental design for a gunner's cupola for an armored vehicle, as shown and described.
